RAYMOND D. SMITH, OF SCARSDALE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

THERMOSTATIC PLURAL-LAMP FULL SOCKET.

Application filed November 8, 1920, Serial No. 422,750. Renewed May 18, 1926.

This invention relates to improved socket switches, and preferably, though not exclusively, to pull-sockets, incorporating in novel and advantageous combination a plurality 5 of different and convenient light-controlling functions, which, in preferred form, are selectively available by the user.

In general, the object of the present invention is to provide a socket (and specifically, 10 though not exclusively, a pull-socket) having a greatly increased field of usefulness in its control of both the degree and periodicity of illumination produced by incandescent lamps, through the above mentioned novelly 15 combined features of switch function,—such features in the present instance comprising preferably the ability, through consecutive full or partial strokes on the single switch-operating pull chain of a pull-socket, selectively 20 and respectively to switch into and out of circuit a main lamp of desired candle power for full illumination, or so to control a lamp of less candle power, that may be mounted rigidly and laterally on the 25 socket structure to serve as a pilot or night light (in absence of illumination by the main incandescent lamp), and the ability, when through with the full light of said main lamp, to operate the switch in the usual manner 30 and to cause thereby delayed, thermostatically controlled, automatic extinguishment of the main lamp an appreciable interval of time after actuation of the pull chain, so that full illumination may be had for 35 leaving the premises.

A specific object of the present invention is so to arrange the circuit connections that the small wattage lamp of less candle power may be energized by connecting the same to 40 the supply circuit in series with the main lamp, a condition under which the filament of the latter acts as a faintly luminous resistance to cut down the voltage across the terminals of the brightly luminous low wattage lamp. The current passing through the latter is thus less than would be the case were the small lamp connected directly across the supply line, and accordingly the normal life 45 of the low wattage lamp is longer and it is possible to employ, as such lamp, a miniature bulb containing a shorter filament than would otherwise be the case. This last-men-

tioned feature of electrical arrangement may obviously be embodied in a plural lamp socket irrespective of the automatic thermo- 55 static extinguishing device.

A further object is to provide a simple arrangement of switch-controlling mechanism which shall render the switch manually and selectively operable to a maximum degree as 60 to the sequence of operative effects resulting from successive single pulls upon the control chain, and specifically, but not necessarily, so that consecutive full pulls upon the switch-operating chain shall operate alternately to 65 light and extinguish the main lamp in the usual manner, but so that either of the heretofore described special light-controlling switch functions are available at will through less than a full or complete actuating stroke 70 upon the pull-chain.

Other objects reside in the retention, in my improved pull-socket having these several functions, of substantially all the important and advantageous features of modern conventional design and construction of socket switches, so that any new parts employed for producing the new functions heretofore recited are readily adaptable for production 75 through the usual processes of lamp socket 80 manufacture. Such features include the method of securing the stationary inclined contact plates to the insulating socket base; the provision of rugged and readily accessible binding posts for connection of the lead 85 wires, as is desirable and even essential in the commercially successful socket structure; and the telescopic assemblage of the interior switch structure with the outer enclosing and supporting casing, free of interference with the laterally mounted pilot lamp 90 or other new parts.

For purposes of illustration only, the present improvement is disclosed as embodied in a fixture or permanent type of pull-socket as 95 appears in the accompanying drawings in which:

Fig. 1 is a plan view of my improved pull-socket with casing and upper insulating cap omitted and certain parts shown in section 100 for clearness, the position of the switch being that in which the main lamp alone is operatively supplied with current.

Fig. 2 is a view in front elevation, show-

ing the complete pull-socket switch, with the casing and certain other parts broken away to show the interior parts.

Fig. 3 is a diagram of electrical connections.

Fig. 4 is an enlarged view of the current switching parts, showing the rotor advanced to engage the detent hook.

Fig. 5 is a partial view in elevation looking at the right of Fig. 2, with casing broken away.

In the drawings, a single part when appearing in more than one view is designated by the same reference numeral.

15 My improved socket-switch is composed as usual of an insulating cap 10 and an insulating base 11 held by screws to the electrically insulated bell-mouth bracket 13, and to the binding post brackets 14 and 15, the former of which carries a small insulated threaded receptacle 16 for the miniature pilot lamp 59, and is electrically connected with the threaded receptacle 17 for the main lamp 67 by means of the holding screw 18 (Fig. 1).

20 The central, vertical pivot stud 20 is adjustably seated in recesses formed respectively and centrally in the insulating cap and base, and pivotally carries the usual oscillatory segmentary actuator 21, the coiled spring 22 for rotatively returning the latter after its stroke, and the double-ended conductive rotor 23, all of these parts being axially slidable upon the insulated pivot 25 stud 20 and pressed axially downwardly thereon against inclined detent steps 34, 35, and 36 formed on the insulating base 11, by the axial tension in said spring 22 as in the common form of pull-socket switches well 30 known in the art. The present improvement contemplates the accomplishment of the cited objects principally through the rearrangement of stationary contact plates carried on the inclined faces of said detent 35 steps, over which the wiper 23 rides under tension of spring 22 to make and to break the circuits.

40 A ready understanding of the nature of this rearrangement of contact plates may best be had through comparison thereof with the usual and well known arrangement of corresponding contact plates in the simple, conventional type of make-and-break pull socket switch. In the latter type of switch it is well known to those skilled in the art that the circuit is controlled through the rotation of the rotor wiper arms 25 simultaneously over diametrically opposite and similarly inclined detent steps, such steps being generally of 90° circular extent and four in number, and a pair of opposite steps carrying contact plates connected as suitable circuit terminals for connecting the lamp to the supply circuit when conductively bridged by the rotor arms. Also in the familiar

switch construction just described, it is well known that each of said incline steps terminates in an abrupt insulating shoulder formed on the insulating base, to prevent retrogressive movement of the rotor arms 70 25 between steps.

In Figs. 1 and 3 of the drawing, four such insulating step shoulders 30 appear in equally spaced relation, these shoulders being understood to occupy a position relative to the heretofore described switch parts substantially the same as in the simple conventional make-and-break type of pull-socket switch before mentioned. This construction gives rise to the usual operation, i. e., so that the actuator (which is normally positioned against stop 31 depending from bracket 15 and is free for limited swinging movement between said stop and the dummy bracket 32), possesses an oscillatory travel 35 of slightly more than 90°, the latter being substantially the uniform spacing of step shoulders 30, so that the actuator, at each full stroke thereof, drives the rotor 23 by ratchet engagement therewith so that each 40 of the arms 25 is advanced completely over one detent step and its terminating step shoulder 30 with a quick snap action and onto the succeeding step such action taking place simultaneously with both rotor arms. 45 But in the present improvement, two of the above described ratchet steps, (specifically those steps which, in the simple make-and-break type of pull-socket switch, are blank) are divided in halves, and two additional insulating shoulders 33, 33 are formed producing two inclined detent steps 34, and 35 50 in place of each of the original blank steps. 55

Thus there are in my improved socket one pair of contact carrying steps 34, 35 of 90° 60 extent, angularly separated by two pairs of 45° steps, one of which latter pairs, comprising steps 34, 34, is blank and the other pair 35, 35 carrying auxiliary contact plates, for governing the pilot lamp 59. 65

70 The electrical connections of these step-carried and inclined contact plates are evident from Fig. 3, it being noted that a single supply circuit contact 40 occupies both steps 35 and 36 on one side of the switch; 75 that a single contact plate 41 occupies the opposite short step 35, and that two separate contacts 42 and 43 occupy the base and top 80 respectively of the other detent step 36.

85 Contacts 40 and 43 each terminate diametrically opposite each other and at their uppermost portion, in the angular formation shown in Fig. 4, where the end of the wiper arm is shown as having rotatively passed the apex or summit of this angular 90° formation, and positioned on the sloping terminal of contact 43 to be discharged therefrom by the axial tension in spring 22. The detent hook 44, however, is pivoted on the 95 base mounted stud 45 and is normally po- 100

sitioned to engage with one of the two spurs 46 on the wiper arms to prevent such discharge until the thermostat 50 (which carries an insulated heating resistance winding 51 electrically connected to be energized only in the position of the rotor as shown in Fig. 4) is heated by the current passing through said winding and flexes outwardly to retract the hook 44 from the path of spur 46 and permit the wiper arms 25 to be discharged simultaneously as described from contacts 43 and 40 to break the circuit through the main lamp.

The electrical connections through the switch as diagrammatically indicated in Fig. 3 are produced in the structure as follows.

The long contact plate 40 is extended to be clamped beneath binding post bracket 15 in the usual and well known manner, as shown in Fig. 5. The short contact plate 41 is extended and secured to the insulating base 11 by a screw 60 and retaining nut 61. Another conductive strip 62 is also clamped beneath the head of screw 60 and extends to electrical contact with a holding screw 63 for the small threaded receptacle 16 for a miniature lamp 59. Said receptacle and screw, however, are entirely insulated from the binding post bracket 14, as is evident from Fig. 1, and a separate conductive strip 65 extends from the miniature lamp receptacle 16 to electrical contact with a radially outward extension 66 of contact 42. Contact 42 has also an inward extension electrically connected to the contact tongue 64 for the main lamp as usual. Both the strip 65 and extension 66 are clamped between the base 11 and the bell-mouth bracket 13, the latter being completely insulated therefrom by fibre, mica, or other suitable material 73. Also thus clamped in electrical contact with the extension 66 of contact 42, is one end 70, of a connection lead from the thermostat resistance winding 51, the other end of which winding has a connection lead 71 extending to beneath the head of a screw 72, which in a manner similar to screw 60 firmly holds contact 43 to the insulating base.

My improved switch operates as follows:

In Fig. 1 the rotor 23 is shown in a position bridging and electrically connecting contacts 40 and 42. Current is thus supplied directly to the main lamp which is thus adapted for continuous burning at full brilliancy.

When desired to extinguish the main lamp, a stroke upon the pull-chain 75 will cause the actuator 21 to advance the rotor 23 from its position indicated by broken lines (at the left and above contacts 42 and 43) into its position as shown in full lines in Fig. 4, where resistance is offered to the further travel of said rotor by engagement of hook 44 with spur 46 formed on the rotor arm 25, such resistance being readily felt by the

hand of the operator. If it be desired to cause delayed extinguishment, the chain is then released and the wiper remains in its arrested position until released by the thermostatic action as heretofore described. If it be desired to effect immediate extinguishment without delayed action, the stroke on the pull-chain is completed against the resistance of hook 44, which as shown in Fig. 1 is bevelled in a manner to produce a re-75 tracting tendency of the detent hook when the latter is subjected to a sufficiently strong thrust by the spur 46. The light is now extinguished and the wiper arms occupy a position as indicated in broken lines in Figs. 80 3 and at the right of contact 43 in 4.

The operative effect of the next single actuation of the pull chain 75 is also optional. A half stroke on the chain suffices to rotate the wiper to a position for bridging contacts 40 and 41, in which position the auxiliary lamp 59 and main lamp 67 are connected in electrical series to the supply circuit;—or a full stroke on the chain advances the wiper to its operative position shown in Fig. 1, 90 where the main lamp alone is energized and burns at full brilliancy.

It is thus evident that consecutively full strokes upon the chain will operate merely to light and extinguish the main lamp in the usual manner, but that if suitable partial strokes be given to the pull chain the operative effects of delaying the extinguishment of the main lamp and of establishing the pilot lamp in circuit may be secured selectively at their respective places in the cycle of operative movements.

It will be understood, however, that no restrictions are intended to be imposed upon my invention through illustration of this particular sequence of operation. The sequence with which these operations may be had is merely a matter of choice in predetermined arrangement; and it will be clear that the automatically delayed acting means may as readily be arranged to transfer current from the main to the pilot lamp, or vice versa, or even to extinguish the small lamp automatically as may be desired.

Particular attention is called to the slotted construction at 68 of the casing 76 whereby usual telescopic assemblage of such casing with its contained switch structure may be had without interference by the laterally protruding pilot lamp receptacle 16. An insulating sleeve 78 completely surrounds said receptacle.

A curved chain guard 77 is shown extending from and secured to the bell-mouth bracket 13 and may be formed of fibre or other suitable material for insulating the conductor strip 62 from accidental contact by the pull chain 75, or other moving parts.

The usual metallic casing cap 80 may be removably interlocked with the casing 76 in

any suitable way, it being noted, however, that in its entirety the advantageous switch arrangement which I have invented and herein described is as readily capable of embodiment in an adapter type of socket, or a pendant pull switch, etc., as in the permanent or fixture type of lamp socket herein shown.

It is also noted that although Fig 3 indicates what is termed a series connection of the thermo resistance connection relative to the main lamp, that an arrangement of connections could as well be utilized whereby the thermostatic heating resistance would be energized by being placed in shunt to the lamp.

The feature residing in the thermostatic control mechanism, per se, including members 42, 43, 44, 45 and 59, is not claimed in this application, but is the subject matter of claims in my two copending applications, Serial No. 421,556, filed Nov. 3, 1920, and Serial No. 421,555, filed Nov. 3, 1920. Also the feature residing in the operative arrangement of contact steps 30, 33, 34, etc. relative to the rotor 23 and in combination with the pilot lamp receptacle 16 and its electrical connections, is not claimed in this application but is the subject matter of claims in applicant's co-pending application Serial No. 504,494, filed Oct. 27, 1919, as are also the features of construction and mounting of said pilot lamp receptacle 16, per se.

Many modifications of the exact embodiment of my invention as herein disclosed, may be readily made;—and without intention, therefore, of limiting the scope of the invention to such exact embodiment, what I claim as new is:

1. A socket switch having two lamp receptacles arranged to receive respectively a relatively high and a relatively low wattage lamp;—electrically controlled means operative when energized to cause the automatic circuit disconnection of one of said receptacles;—and contained switch mechanism including separate stationary contacts for circuits operatively related respectively to each of said receptacles and to said means, together with a single manually-actuable circuit-governing element mounted for movement relative to, and engagement with, said contacts, whereby either of said receptacles or one of said receptacles and said means may be selectively connected to the supply circuit.

2. A socket switch having two separate lamp receptacles adapted to receive respectively a relatively high and a relatively low wattage lamp; electrically controlled means operative when energized to cause the automatic disconnection of one of the receptacles from the circuit; and a contained switch embodying a single-acting movable member arranged to be manually actuated, station-

ary contacts arranged to be placed, respectively, in operative electrical series with each of said receptacles at different positions of said member, and an auxiliary stationary contact arranged co-operatively with the stationary contacts governing one of said receptacles to connect said means and said last mentioned receptacles to the supply circuit at another position of said member.

3. A socket switch having two separate lamp receptacles adapted to receive respectively a relatively high and a relatively low wattage lamp; electrically controlled means operative when energized to cause the automatic disconnection of one of said receptacles from the circuit;—and a contained switch embodying a single-acting movable member arranged to be manually actuated, stationary contacts arranged to be placed, respectively, in operative electrical series with each of said receptacles to energize the same at different positions of said member, and auxiliary stationary contacts arranged to connect said means and one of said receptacles to the supply circuit at another position of said member.

4. A pull-socket switch having two separate lamp receptacles adapted to receive respectively a relatively high and a relatively low wattage lamp; electrically operated means operative when energized to cause the automatic disconnection of one of said receptacles from the supply circuit; and a contained switch mechanism embodying a rotatable current-switching contact-wiper arranged to be manually driven through successive stages of movement by pawl-and-ratchet engagement therewith of a spring returned oscillatory actuator; stationary contacts arranged to be successively contacted by said contact-wiper and electrically connected respectively to each of said receptacles, whereby the latter are energized at different positions of said member; and an auxiliary stationary contact arranged co-operatively with one of the receptacle-connected stationary contacts to connect said means and one receptacle to the supply circuit at another position of said member; together with a single pull element for oscillating said actuator to establish the connection and disconnection of said receptacles and said means respectively to the supply circuit.

5. A pull-socket switch having a main and an auxiliary lamp receptacle; electrically operable means adapted when energized to cause the automatic disconnection of one of said receptacles from the supply circuit; and a contained switch mechanism embodying a current-switching rotor, arranged co-operatively with an oscillatory actuator having pawl-and-ratchet engagement therewith to be rotatively advanced in full stages of movement by full strokes of said actuator;

- stationary supply-circuit contacts positioned to be wipingly traversed by said rotor, connected to said receptacles respectively, and so consecutively spaced that two of said contacts are traversed by said rotor within a said full stage of movement thereof, thereby to control the energization of both said receptacles by a full stroke of said rotor; and an auxiliary contact arranged co-operatively with one of said stationary contacts to be contacted by said rotor for energizing said means when one of said receptacles is energized, and upon further movement of said rotor; together with a single pull element adapted for imparting full or partial strokes to said actuator; whereby said switch rotor may be selectively established in either of two operatively different positions by a single pull on said element.
20. 6. A pull socket switch having two separate lamp receptacles adapted to receive respectively a relatively high and a relatively low wattage lamp; electrically operated means operative when energized to cause the automatic disconnection of one of said receptacles from the supply circuit; and a contained switch mechanism embodying a rotatable, centrally-pivoted current switching member having two diametrically opposite contact wiping arms, a concentrically pivoted driving segment having stop means to limit the swing thereof and having pawl-and-ratchet engagement with said member, whereby successive oscillations of said segment rotatively advance said plate in stages, and a coiled spring connected to said segment rotatively to return the same and axially to press said wiper arms against stationary inclined detent steps terminating in abrupt insulating shoulders for preventing retrogressive rotation of said arms between steps, a plurality of said steps being circularly disposed in the path of each of said arms and within a single stage of the said rotative advance thereof; stationary, circuit-terminal, contact plates positioned on said inclined steps to be electrically connected in diametrically-opposite pairs by said arms and electrically connected to said receptacles respectively, whereby the latter are energized in predetermined electrical relation at different rotative positions of said arms; and an auxiliary stationary contact plate arranged co-operatively with the first said contact plates to connect said means and one of said receptacles to the supply circuit at another position of said arms; together with a single pull element for causing full or partial oscillations of said segment, whereby a selective sequence of supply circuit connection of said receptacles and said means respectively is had.
35. 7. A plural-lamp-governing socket switch structure including, in combination; two lamp-receiving receptacles mounted on the switch structure; a double-ended, current-switching, conductive rotor; two spaced and stationary main contacts positioned to be conductively engaged and disengaged simultaneously by said rotor; for respectively connecting and disconnecting one of said lamp receptacles and the supply circuit; auxiliary stationary contacts positioned in the path of said rotor and circularly spaced intermediate said main stationary contacts respectively; and circuit connections whereby contact of said rotor with said auxiliary stationary contacts energizes both of said receptacles in series.
40. 8. A plural-lamp socket switch structure including, in combination; two lamp-receiving receptacles mounted on the switch structure; a double-ended, current-switching, conductive rotor; two spaced and stationary main contacts positioned to be conductively engaged and disengaged simultaneously by said rotor; for respectively connecting and disconnecting one of said lamp receptacles and the supply circuit; auxiliary stationary contacts positioned in the path of said rotor and circularly spaced intermediate said main stationary contacts respectively; and circuit connections whereby contact of said rotor with said auxiliary stationary contacts energizes both of said receptacles in series.
45. 9. In a plural-lamp socket switch structure embodying a movable contact member and automatic actuating means therefor tending when manually energized to move said member to a circuit-breaking position, in combination; receptacles for receiving a plurality of lamps; supply circuit terminals for the connection of said structure to a supply circuit; a device normally arranged to intercept circuit breaking movement of said member and electro-thermally energizable for permitting said movement after a substantial period of delay; stationary contacts positioned to be conductively traversed

by said member for switching the current; and circuit connections between said terminals, said receptacles, said device, and said contacts, so arranged that contact of said member with different stationary contacts respectively controls the supply of current to said lamps individually and operatively controls the energization of said device.

10. In a current-supplied socket switch structure having receptacles for a main and auxiliary lamp respectively, and embodying a manually operable switch with an electrically energizable automatic device normally operative to delay the cut-off by said switch 15 of current to one of said lamp receptacles, and manually actuatable means to control the energization of said device, in combination; a movable switch-contact member operably related to said device and to said means; a plurality of stationary contacts positioned to be conductively traversed by said member for controlling a plurality of circuits; and electrical connections between the supply, said receptacles, said device, and said 20 stationary contacts comprising said circuits and so arranged that, in one position of said member, current is supplied to the auxiliary lamp, in another position of said member current is supplied to said main lamp, and 25 in a different position of said member current is supplied to energize said device for effecting delayed automatic movement of said member to a circuit breaking position.

11. A socket switch and plural lamp arrangement having a main high wattage lamp, and auxiliary low wattage lamp, and automatic electrically-operative means to cause the delayed cut-off of current through the main lamp;—together with a switch 30 comprising stationary contacts governing three circuits respectively containing said lamps and said means; and a co-operative manually movable circuit controller arranged by a first movement thereof to energize said low wattage lamp, by a second movement to energize said main lamp and by a third movement to energize said means together with said main lamp thereby to cause the delayed cut-out of said main 35 lamp.

12. A pull-socket switch and plural-lamp arrangement having a main high wattage lamp, and automatic electrically controllable means to cause the delayed cut-off of current through the main lamp;—together with a switch comprising stationary contacts governing three circuits respectively containing said lamps and said means; and a co-operative rotatable circuit controller 40 having a pawl-and-ratchet driving device therefor arranged by one stroke thereof to position said controller to energize said low wattage lamp, by a second or further stroke to position said controller to energize said main lamp, and by a subsequent stroke there-

of to energize said means, together with said main lamp, thereby to cause the delayed cut-out of the latter.

13. The combination with receptacles for a plurality of lamps, one of high and the other of relatively low wattage, of a circuit controlling member movable to light and extinguish said lamps, and means automatically to retard the extinguishment of the lamp of high wattage for a substantial period of time after the initiation of the lamp extinguishing movement.

14. In a lamp socket switch, a plurality of lamp sockets, a circuit controlling member movable separately to light or extinguish the lamp, and means automatically to retard the extinguishment of one of said lamps after initiating the movement of said member.

15. The combination with a plurality of lamp sockets, of switching means for alternately lighting and extinguishing the lamps thereof, and means automatically to retard the extinguishment of one of said lamps after said switching means has been given a movement for the extinguishment of said lamp.

16. The combination with receptacles for a plurality of lamps, one of high and the other of relatively low wattage, of a switch therefor including a contact controlling member, a switch control member and a thermo-electrically controlled device for said switch to retard movement of the same after the movement of said switch control member.

17. An electric switch having contacts for a plurality of lamps, contact controlling means for effecting a circuit change first in one and then in the other of said lamps, means manually to initiate the circuit changing action thereof, and a thermo-electric device with a circuit therefor, the latter being conditioned by the circuit controlling means when actuated to initiate a circuit change in one of said lamps to delay said circuit change until after the lapse of a substantial period of time.

18. An electric switch having contacts for a plurality of lamps, a movable contact controller for effecting a circuit change first in one and then in the other of said lamps, and means conditioned by the movement of said contact controller to effect a circuit change in one of said circuits for automatically delaying said circuit change.

19. An electric switch having contacts for a plurality of lamps, contact controlling means for effecting a circuit change first in one and then in the other of said lamps, and a delayed action control conditioned by the movement of said contact controlling means to effect a given circuit change automatically to delay said circuit change.

20. The combination with receptacles for

a plurality of lamps, of an electric switch having an actuator, and means alternately to light said lamps through movement of said actuator, said switch incorporating agencies automatically operative to retard extinguishment of one lamp for a substantial period of time following the movement of said actuator designed to effect said extinguishment.

21. The combination with receptacles for a plurality of lamps, of an electric switch having an actuator, and means alternately to light said lamps through movement of said actuator, said means including a contact controlling member having a lighting position for one lamp, a lighting position for a second lamp and an intermediate position where both lamps are extinguished, said switch incorporating agencies automatically operative to retard extinguishment of one lamp for a substantial period of time following the movement of said actuator designed to effect such extinguishment and prior to the movement of said contact controlling member to said intermediate position.

22. The combination with receptacles for

a plurality of lamps, of a pull chain lamp socket switch having an oscillatory actuator, and a rotary contact controlling member, the latter movable alternately to light said lamps, with an intermediate position providing for extinguishment of both lamps, said switch incorporating agencies automatically operative to retard the movement of said contact controlling member to a position of lamp extinguishment for a substantial period of time following the movement of said actuator designed to effect such extinguishment.

23. The combination with a plurality of lamps, of circuits therefor operative to light or extinguish the same, switching means, controlling means for the switching means, and means set into operation by the lamp extinguishing movement of said controlling means automatically to delay said lamp extinguishment for a substantial interval.

Signed at Boston, in the county of Suffolk and Commonwealth of Massachusetts, this 5th day of November, 1920.

RAYMOND D. SMITH.
